(57) **CLAIM**

We claim the ornamental design for a light emitting diode module, as shown and described.

DESCRIPTION

FIG. 1 is a top perspective view of a light emitting diode module of the present invention;
FIG. 2 is a front view thereof;
FIG. 3 is a top view, the bottom view being a mirror image thereof;
FIG. 4 is a first side view thereof;
FIG. 5 is a second side view thereof; and,
FIG. 6 is a rear view thereof.
